UNITED STATES PATENT OFFICE

HERBERT S. POWELL, OF UTICA, NEW YORK

MACHINE FOR BENDING FLAT METAL STRIPS INTO SPIRALS

Application filed April 13, 1928. Serial No. 269,639.

My invention relates to a machine for bending flat metal strips into spirals, and I declare the following to be a full, clear, concise and exact description thereof sufficient to enable anyone skilled in the art to which it appertains to make and use the same, reference being had to the accompanying drawings in which like reference characters refer to like parts throughout the specification.

The object of the invention is to provide a machine that will bend or twist a flat strip or band of metal into a spiral. The flat strip thus bent into a spiral is cut at the proper length for use more particularly in the mufflers of exhaust engines, whereby to cause the exhaust gases to take a swirling course as it passes through the rear part of said muffler.

The object will be understood by referring to the drawings in which:

Fig. 1 is a perspective view of the device showing parts broken away;

Fig. 2 is a central vertical section taken on the line 2—2 of Fig. 1, parts being shown in full and parts broken away;

Fig. 3 is a detail view of the metal strip after passing through the machine; and

Fig. 4 is a detail view somewhat enlarged showing a perspective of a universal joint employed.

Referring more particularly to the drawings, the device embodies the frame comprising upright standards 1, 1 mounted on a stationary base 2. Each of the standards 1 has an open upper portion that is enclosed on the top thereof by cover plates 3, 3. The open recesses in standards 1 are adapted for the sliding movement of vertically movable bearing blocks 4, 4 in which is journaled the respective ends of shaft 5. A roller 6 made preferably of some heavy material is mounted to turn with shaft 5. Directly below roller 6 is roller 11 of the same size and material. Roller 11 is mounted to turn with shaft 12 having bearings in walls 13, 13 of standards 1, 1.

The means for holding upper roller 6 in spaced relation to lower roller 11, whereby to allow for any given thickness of metal strip passed therebetween, embodies the above mentioned vertical movable bearing blocks

4, 4. The outer ends of blocks 4, 4 are shouldered at 15, 15 to ride against the rails 16, 16 made integral with the respective standards 1, 1. Bearing blocks 4, 4 are supported in predetermined position by coiled springs 20, 20 that rest at one end on the respective surface of shelves 21, 21 formed in standards 1, 1. The upper ends of coiled springs 20, 20 are coiled about depending shafts or studs 22 secured or formed integral with the lower surface of each of bearing blocks 4, 4. Studs 22, 22 extend a short distance only into springs 20, 20 whereby to hold said springs 20, 20 in position. Springs 20, 20 tend to force bearing blocks 4, 4 upward. They are moved downward, however, against the tension of springs 20, 20 by adjustable screw bolts 25, 25 mounted in each instance in the cover plates 3, 3. The lower end of each of the screw bolts 25 rests upon the upper surface of a bearing block 4, whereby to hold said block in predetermined position. Lock nuts 26, 26 are mounted in each instance upon adjustable screw bolts 25, 25 which nuts 26 can be turned down against the upper surface of cover plates 3, 3 to lock screw bolts 25 in given position.

Upper shaft 5 with which roller 6 revolves is extended laterally and united to a connecting link 30 by a universal joint formed by bifurcating the ends of shaft 5 and link 30 respectively and pivoting said ends to block 30^a by pivots 30^a, 30^b. Link 30 is joined in turn by universal joint at 32 to shaft 33 which has bearings in auxiliary standard 34. A spur gear 35 is mounted to turn with shaft 33. Spur gear 35 is in mesh with spur gear 36 of like diameter and mounted to turn with shaft 12 with which roller 11 also revolves. A spur gear 40 of much smaller diameter is in mesh with spur gear 36. Spur gear 40 is mounted to turn with shaft 41 having bearings in the walls 37 of auxiliary standards 34, 34. A pulley 42 is fixed to turn also with shaft 41. Pulley 42 is connected by a belt 43 with a power pulley, not here shown.

The means for bending or twisting the metallic band 45 embodies rotatable disks 50 and 51, which are mounted on plate 52 held in spaced relation from standards 1, 1 by four

brackets 55 that are connected by bolts 56 to the standards. Plate 52 has a round central recess 57 disposed opposite an imaginary plane passing between rollers 6 and 11, whereby metal strip or band 45 can pass from between rollers 6 and 11 through plate 52 and disks 50 and 51.

Disk 50 has a central annular elevation 58 on one face thereof that fits within the annular recess 57 of plate 52 in such manner as to turn therein. It has a central recess 60 for the passage of metal strip 45. Disposed adjacent said recess 60 are two rollers 61, 61 mounted to rotate on shafts 61^a, 61^a carried at each end in a bearing block or shelf 62 of which there are two oppositely disposed. Rollers 61, 61 are spaced apart for the passage of metal strip 45. Bearing blocks 62, 62 are formed integral with disk 50. Set-bolts 63, 63 are screw-mounted in bearing blocks 62, 62 and are adapted to engage countersunk recesses made in shafts 61^a, 61^a, whereby to hold said shafts in position.

Likewise disk 51 has a central recess 70 and mounted adjacent thereto are rollers 71, 71 spaced apart and on shafts 71^a that are journaled in blocks 72, 72 formed integral with disk 51 and held therein by similar set bolts 63.

Disks 50 and 51 are held in assembled relation to plate 52 by bolts 75, 75 that are projected through alined sector recesses 76, 76 made in disks 50 and 51 and into threaded apertures in plate 52. Washers 78, 78 are on bolts 75 adjacent the heads thereof to span recesses 76, 76. Handles 80^a, 81 are bolted to disks 50 and 51, whereby to rotate the same with relation to each other in order to move the sets of rollers 61, 61 and 71, 71 to bend or effect a spiral to metal band or strip 45.

A bracket 85 is bolted to standards 1, 1 to aid in directing band 45 between rollers 6 and 11. It has mounted thereon two adjustable posts 80, 80 provided with an open recess in each instance, whereby to straddle the edge of bracket 85. Set bolts 86, 86 are employed to hold said posts 80, 80 in given position. An adjustable shaft or pin 87 is carried in apertures made in adjustable posts 80, 80 to span the space between posts 80, 80 whereby to prevent metal strip 45 from moving upward therpast. In operation metal strip 45 is fed from a spool, not shown, between posts 80, 80 under pin 87 and through rollers 6 and 11 and thence between the two sets of rollers 61, 61 and 71, 71. Disks 50 and 51 will be rotated in the first instance, whereby to bring the spaces between said sets of rollers in alinement with the horizontal plane of strip 45 to be twisted. Thereafter disks 50 and 51 can be turned at any angle to each other to effect a given spiral to metallic strip 45.

The turning of master pulley 42 will actuate the train of gears consisting of smaller spur gear 40, large spur gears 36, 35, whereby

to rotate shafts 12 and 33 respectively and hence rollers 6 and 11. The rotation of rollers 6 and 11 will push metallic strip 45 through the sets of rollers 61, 61 and 71, 71 to effect a spiral to strip 45 in accordance with the relative positions to which said sets of rollers 61, 61 and 71, 71 are disposed to each other by manipulating handles 80^a and 81 of disks 50, 51 respectively.

Having thus described my invention what I claim is new and desire to secure by Letters Patent, is as follows:

1. In a machine for bending flat metal strips into spirals, means for feeding a strip of metal in one plane, and rotary disks having rollers mounted thereon for twisting said strip of metal in other planes.

2. In a machine for bending flat metal strips into spirals, rollers for twisting a strip of metal into a spiral, other rollers for pushing said strip of metal through said first-named means, and means for turning said first-named rollers relative to each other.

3. In a machine for bending flat metal strips into spirals, adjustable rollers for feeding a strip of metal in one plane, and movable sets of rollers located adjacent said first-named rollers, whereby to twist said strip of metal into a spiral.

4. In a machine for bending flat metal strips into spirals, adjustable rollers for feeding a strip of metal in a given plane, and rotatable disks having rollers mounted thereon for bending said strips of metal into a spiral.

5. In a machine for bending flat metal strips into spirals, adjustable rollers for actuating a strip of metal in a given plane, rotatable disks mounted adjacent said adjustable rollers, and other rollers rotated on said disks, whereby to aid in twisting said strip of metal into a spiral.

In testimony whereof I have affixed my signature.

HERBERT S. POWELL.
